UNITED STATES PATENT OFFICE.

ADOLPH J. JARMUTH, OF SEATTLE, WASHINGTON, ASSIGNOR TO ERASTUS S. BENNETT,
OF NEW YORK, N. Y.

GOLD-SAVING APPARATUS.

1,271,714.

Specification of Letters Patent.

Patented July 9, 1918.

Application filed December 17, 1915. Serial No. 67,433.

To all whom it may concern:

Be it known that I, ADOLPH J. JARMUTH, a citizen of the United States, residing at Seattle, Washington, have invented certain new and useful Improvements in Gold-Saving Apparatus, of which the following is a specification.

The invention relates to a gold saving apparatus of the general type disclosed in Letters Patent of the United States granted 10 to Erastus S. Bennett, April 2nd, 1907, No. 849,101, and concerns particularly the construction and arrangement of the pockets shown in said patent on the inclined sides 15 of the tank.

The invention consists in the features and combination and arrangement of parts hereinafter described and particularly pointed out in the claims.

20 In the accompanying drawing

Figure 1 represents a sectional view of a portion of the inclined side of the tank with my improvements combined therewith.

Fig. 2 is a face view of a portion of a tier 25 of pockets. Fig. 3 is a detail perspective view.

In carrying out the invention I aim to provide a continuous surface of non-oxidizable material having an affinity for the 30 mercury extending from the uppermost pocket of the tier to the lowermost pocket thereof, and, in carrying out this feature of the invention, I still employ the aprons shown in the above mentioned patent, ex- 35 tending from one pocket to another, but with my improvement I extend the non-oxidizable material of the apron to form the mercury holding pocket itself or, to express it in another way, to provide a lining 40 for the main pocket or support which is at- 45 tached to the inclined side of the tank so that the mercury at all points may be in contact with a metallic surface, with which it has an affinity to provide an unbroken mercury body or covered surface to prevent the sand from reaching a point where it 50 would tend to displace the mercury.

In the drawings, 1 indicates the inclined side of the tank and 2 indicates bars or rails 55 arranged in pairs and substantially, though removably, hung or attached to the tank side, and while this may be accomplished in various ways, I prefer to form the rails with a hooked upper end which may engage over the upper edge of the tank and thus sus- 60 pend the said rails in place or clamp screws 65 may be used. These rails, as before stated, are arranged in pairs and each pair serves to carry the supporting means for the pockets and aprons, and while these supports 70 may be of various forms, I have illustrated them in the form of troughs or pocket shaped members 3, which may be of non-amalgamable material, the ends of which troughs or pocket-like supports are riveted 75 at 4 to the said rails or side bars and forming with the pair of rails, a ladder like structure, which may be removed from or replaced in the apparatus as one body. These supports 3 hold the mercury receptacles or pocket linings which consist of sheet metal of trough form, shown at 5, provided with end portions or walls 6, the troughs or pockets being of such dimensions as to fit close against the end walls of the support- 80 troughs 3 and to rest on the bottoms of said supporting members. This sheet metal, of which the mercury holders or pocket linings are made, is of non-oxidizable metal or metal having a non-oxidizable coating, 85 such as silver, having an affinity for the mercury. From the front edge of each mercury holding pocket or receptacle an apron 90 extends downwardly into the mercury holding pocket or container next below it and preferably the end of this apron is turned inwardly so as to lie along the wall of the next lower pocket lining and it extends far enough to be immersed in the body of the mercury and it forms substantially 95 a continuous silvered surface from the front edge of one pocket to the outer or rear wall of the next pocket below and to a point below the surface of the mercury therein. It will be understood that a tank for the purpose described, namely of saving gold, is 100 agitated, as stated in the patent before referred to, and a sufficient body of mercury is held in each pocket so that a wave-like motion is produced along the surface of the 105 mercury, due either to the vibration of the machinery or to means directly causing said vibration, the effect of which motion on the surface of the body of mercury is to break up and reduce the section of sand which naturally tends to rest on the surface of the 110 mercury and which would otherwise pack thereon and prevent the passage through it of the gold into the pockets. The wave-like motion keeps the sand loosened and gravi-

tating particles of gold or ore can readily pass through the sand into the pockets. The mercury, however, being contained in a pocket composed of metal or coated with metal having an affinity for the mercury, both as to its end walls and bottom and front sides, the agitation of the mercury will not result in the formation of gaps in its surface adjacent the walls of the pockets which would allow the sand to descend below the surface of the mercury and displace any of the body of the mercury. The mercury is delivered to the apparatus in substantially the same way as in the patent referred to, namely by a pipe at the top of the tank wall. The material in passing over the front edge of the pocket or pocket lining is apt in time to wear this away if provision is not made to prevent this, and I, therefore, reinforce the front edge of the pocket by a strip 8 of non-oxidizable metal or a metal having a non-oxidizable coating, such as silver, this strip being substantially of U shape and simply gripping by its downwardly extending sides the upturned edge of the pocket or lining and the adjacent portion of the upper edge of the apron. This reinforcing or wearing strip may be readily removed and replaced by another when worn. The pockets, or as they may be called the linings of non-oxidizable material, together with their aprons, may be individually removed from the supports 3 in cleaning up, or the whole series or tier of pockets may be removed as one body by simply lifting out the ladder-like structure composed of the rails or sides 2 with the supports 3 and the pocket linings and aprons carried thereby. In order to hold the linings or pockets in place on the supports 3, any suitable means may be provided, but as one means for this purpose I employ spring catches or plates 9 which may be attached to the supports 3 and overlie a portion of the removable lining or pockets, so that by pressing these spring catches to one side the linings may be removed.

The aprons are formed of thin sheet metal and in order to prevent their displacement or distortion by the weight of the material

acting upon them, I provide backing members or filling pieces 10 of sheet metal having their ends 11 bent from the main body and riveted or otherwise secured to the side rails 2. The main portions of these backing pieces lie close against the aprons and support them against displacement.

One principal object of the invention is to make the mercury follow all the surfaces of the pockets or linings therefor and to leave no metal exposed which would have an affinity for the iron sand, or in other words, I get a continuous amalgamated surface from top to bottom of the course of mercury extending through all the pockets and along the full extent of all the aprons.

I claim as my invention:

1. In combination, in a gold saving apparatus, a tank side, a support, a mercury holding receptacle composed of thin sheet metal held by said support and a reinforcing piece removably mounted on and overlapping the edge of said mercury holding member, over which reinforcing piece the material must pass, thereby protecting the said edge, substantially as described.

2. In combination, in a gold saving apparatus, a tank side, a mercury holding pocket having an apron depending from its edge and a reinforcing member removably held at and overlapping the point of junction between the mercury pocket and apron, and protecting said junction point from wear of the passing material, substantially as described.

3. In combination in a gold saving apparatus, a tank side, a mercury holding pocket composed of thin sheet metal, a support for said pocket and a reinforcing piece of inverted U-shape in cross section removably mounted on the edge of said pocket over which the material must pass, whereby the said edge is protected from the wear resulting from the passage of the material, substantially as described.

In testimony whereof, I affix my signature in presence of two witnesses.

ADOLPH J. JARMUTH.

Witnesses:

ALFRED W. GREENER,
ARTHUR P. BRISBANE.
